(57) **CLAIM**

The ornamental design for an eyewear grip, as shown and described.

DESCRIPTION

FIG. 1 is a front perspective view of an eyewear grip;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The evenly-sized broken lines showing eyewear and another eyewear grip in FIG. 1 depicts environmental subject matter that forms no part of the claimed design, while the remaining evenly-sized broken lines shown in the drawings depict portions of the eyewear grips that form no part of the claimed design, and the unevenly-sized broken lines represent the bounds of the claimed design.

1 Claim, 3 Drawing Sheets
